UNITED STATES PATENT OFFICE

CHARLES O. NEWLIN, OF SEATTLE, WASHINGTON

SPRAY BRUSH

Application filed May 20, 1929. Serial No. 364,603.

The present invention relates to a spray brush which may be used for washing bottles, glasses and other similar receptacles and has for one of its objects to provide a mechanism including a revolving brush which may be brought into contact with the surface of the receptacle to be cleansed and simultaneously discharge water upon the surface of the receptacle which is being washed.

Another very important object of the invention resides in the provision of a device of this nature with means for controlling the flow of water.

A still further very important object of the invention resides in the provision of a device of this nature which is exceedingly simple in its construction, inexpensive to manufacture, strong and durable, thoroughly efficient and reliable in use and operation, compact and convenient in its arrangement of parts, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a top plan view of the device embodying the features of my invention,

Figure 2 is a vertical longitudinal section therethrough,

Figure 3 is an enlarged detail section taken substantially on the line 3-3 of Figure 1,

Figure 4 is a transverse section taken substantially on the line 4-4 of Figure 3,

Figure 5 is a sectional view taken substantially on the line 5-5 of Figure 2,

Figure 6 is a sectional view taken substantially on the line 6-6 of Figure 1.

Referring to the drawings in detail it will be seen that the numeral 5 denotes a base with a pair of bearings 6 and 7 fixed thereto and rising therefrom.

A shaft 8 is journalled in the bearing 7.

The numeral 9 denotes a cylinder with a detachable head 10 at one end and a detachable head 11 at the other end. The shaft

8 is journaled in a stuffing box 12 in the head 10 and has coupled thereto as at 14 a hollow shaft 15 which is journaled in a stuffing box 16 in the head 11 and is journaled in the bearing 6.

A pipe 17 is connected with the center of the cylinder 9. The hollow shaft 15 within the cylinder 9 is perforated as is indicated at 18.

A hollow shaft 20 is coupled to the outer end of the shaft 15 by means of coupling 21. In one end of the shaft 20 there is mounted a perforated valve piece 23 against which is closable a valve head 24 on a stem 25 slideable through the piece 23 and through a plug 26 at the other end of the shaft 20 and terminating at its outer end in a knob or enlargement 27.

A spring 28 impinges against the valve head 24 to normally hold the same closed and engages an annular flange 29 formed in the pipe 15. The pipe 20 is perforated as indicated at 30. A perforated rubber sleeve 31 is mounted over the perforated portion of the pipe 20 and has an extension 32 extending over the coupling 21 and a portion of the outer end of the pipe 15. Bristles 33 radiate outwardly from the rubber sleeve 31 to form a substantially cylindrical brush.

The pipe 17 is preferably connected with a source of hot water and by way of example it will be seen that a bottle may be placed over the brush and when the shaft 8 is rotated by any suitable means the brush 33 will revolve in the bottle. By pushing the bottom of the bottle against the knob 27 the valve head 24 may be forced to an open position so that water will flow through the hollow shafts 15 and 20 out through the apertures 30 among the bristles and spray the interior of the bottle.

Thus the bottle may be thoroughly cleansed in an highly efficient and sanitary manner.

It is thought that the construction, operation, utility and advantages of this invention will now be quite apparent to those skilled in this art without a more detailed description thereof.

The present embodiment of the invention has been disclosed in considerable detail

merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit of the invention as hereinafter claimed or sacrificing any of its advantages.

Having thus described my invention, what I claim as new is:

1. device of the class described comprising a core structure including a hollow shaft, means for mounting bristles thereon, said hollow shaft being apertured among the bristles, a second hollow shaft having an internal flange, a coupling connecting the hollow shafts, a valve seat formed at the end of the first hollow shaft in the coupling, a valve in said coupling between the valve seat and flange, a spring engaging the flange and the valve, a stem engaged with the valve and slideable through the valve seat, and a plug at the other end of the first shaft, said stem being slidably mounted in said plug and extending therethrough, a base, a bearing on said base in which said second shaft is journaled, a cylinder over a portion of said second shaft, said portion of said second shaft being perforated, and means for connecting said cylinder with a source of water.

2. A device of the class described comprising a core structure including a hollow shaft, means for mounting bristles thereon, said hollow shaft being apertured among the bristles, a second hollow shaft having an internal flange, a coupling connecting the hollow shafts, a valve seat formed at the end of the first hollow shaft in the coupling, a valve in said coupling between the valve seat and flange, a spring engaging the flange and the valve, a stem engaged with the valve and slideable through the valve seat, and a plug at the other end of the first shaft, said stem being slidably mounted in said plug and extending therethrough, a base, a bearing on said base in which said second shaft is journaled, a cylinder over a portion of said second shaft, said portion of said second shaft being perforated, and means for connecting said cylinder with a source of water, a second bearing, a drive shaft journaled in said second bearing and extending into the cylinder, and means for coupling the drive shaft with the second mentioned shaft.

In testimony whereof I affix my signature.
CHARLES O. NEWLIN.
